UNITED STATES PATENT OFFICE.

GUILFORD D. ROWELL, OF APPLETON, WISCONSIN.

HOISTING-CARRIER.

SPECIFICATION forming part of Letters Patent No. 271,276, dated January 30, 1883.

Application filed December 8, 1882. (No model.)

To all whom it may concern:

Be it known that I, GUILFORD D. ROWELL, of the city of Appleton, in the State of Wisconsin, have invented certain new and useful 5 Improvements in Hoisting-Carriers, usually known as "Hay-Carriers;" and I do hereby declare that the following is a full, clear, and exact description thereof, reference being had to the accompanying drawings, and to the letters of reference marked thereon, which form a part of this specification.

This invention relates to hoisting-carriers of the class heretofore employed for raising and carrying hay, and which are provided with 15 tripping-blocks for the engagement of the hoisting-tackle block.

The invention has several objects. Among these are, first, to provide a construction in this class of carriers whereby the tripping devices may operate as well at the point of discharging the load as at the point of receiving or hoisting the same, in order that the machine may be used for such purposes as the hoisting, transportation, and lowering of earth in excavations, of shifting freight in freight-buildings, loading and unloading vessels and cars, and distributing freight in vessels and similar situations.

A second object of the invention is to provide a construction in this class of carriers whereby they are adapted to operate at either side of a tripping-block without the necessity of reversing the carriage in the beam or way.

A third object of the invention is to provide 35 for a change of power and speed in the hoist.

To these and other ends which will further appear my invention consists in the matters hereinafter set forth, and pointed out in the appended claims.

40 In the drawings, Figure 1 is a side elevation of the carriage, together with a stationary tripping-block and a fragment of the beam forming the carriage-way. Fig. 2 is a view in elevation of one of the plates of the carriage, showing the locking devices thereto attached, and 45 showing the position of these devices with reference to each other when engaged with the hoisting-block, and also showing the peculiar construction of the tripping-block. Fig. 3 is a view similar to that shown in Fig. 2, but illustrating the locking devices in their position

when the hoisting-block has been released or is about to be engaged thereby. Fig. 4 is a central vertical section through the line *xx* of Fig. 1. Fig. 5 is a detached view, in perspective, of a stationary but removable piece which forms part of the locking devices, and which also serves as a brace for the plates of the carriage. Fig. 6 is a side elevation of the carriage and hoisting-block, in which the latter is 55 provided with two pulleys, and the hoisting-rope is arranged to operate in conjunction with said double pulley-block and the two pulleys of the carriage to give increased hoisting-power. Fig. 7 is an end elevation of the devices constructed and employed as shown in Fig. 6. Fig. 8 is a general view, in side elevation, of the entire carrier as applied to shifting freight.

A and A' are two opposite and parallel plates, forming the body of the carriage R, 60 said plates being respectively provided with the arms *a* and *a'*, to the upper extremities of which are attached the wheels A², intended to travel on the suspended beam or way B.

C C are two loose pulleys mounted between 65 the parallel plates A and A' at opposite ends of the carriage, as clearly shown in the drawings; and D is a hoisting-block, provided with a pulley or pulleys, *d*, a hook, *d'*, at its lower end for engagement with the article to be 70 raised, and a loop or yoke, *d*², at its upper end for engagement with the locking devices of the carriage.

E is a rope trained over the pulleys C C and beneath the pulley *d*, and also, in practice, 75 usually trained over another pulley, B', Figs. 6 and 8, attached to the beam B in position to give the rope E the substantially horizontal direction shown in several figures of the drawings as the same passes from the carriage. 80 Said rope is further usually trained beneath a pulley or snatch block located at or near the ground or floor, whence it leads to the team or other motive power by which the apparatus is 85 worked.

The devices provided in the carriage for engaging and holding the hoisting-block D are located between the pulleys C C, and they consist essentially of the parts F, G, and H. The part F is an angular casting (shown detached 90 in Fig. 5) embraced firmly between the opposing plates A and A' by means of the tie-bolts, which 95

pass through said plates from one to the other. Said casting F has its lower end, f , formed to serve as a stationary hook projecting in a substantially horizontal but somewhat downwardly inclined direction, as shown in Figs. 2 and 3, and being thin enough at this end to stand free and clear from the side plates, A and A', and midway between them, whereby it may enter the yoke or eye d^2 of the hoisting-block. 5

10 G is a tripping-hook centrally pivoted at g^3 , and adapted to swing with its lower end or point, g , into proximity with the end f of the part F, so as to enter the eye d^2 of the hoisting-block, and to thereby sustain or assist in sustaining 15 the latter in place when raised. Said hook G is provided with a projection, g' , located above the point g , against which projection the top of the yoke d^2 strikes in being raised, so as to thereby rotate said hook G on its central pivot, 20 g^3 , and thus bring the point g within the yoke. The upper end of the hook G is provided with a lug, g^2 , which, when the hoisting-block is released, is drawn forward and downward against the upper end of the fixed part F, and is thereby 25 held in the position shown in Fig. 3, with the projection g' extending in the path of the yoke d^2 of the hoisting-block, so as to be struck and lifted, as above described, when said hoisting-block is raised. Said projection g^2 is also intended 30 to engage with the locking-dog H, which is pivoted at h , and is provided with a depending lug, h' , which lug drops in front of the projection g^2 of the tripping-hook G when the latter is swung over by the hoisting-block, and 35 thereby firmly holds said tripping-hook in engagement with the yoke or eye d^2 of said hoisting-block, as shown in Fig. 2.

I is a trip-block secured to the beam B at any desired point beneath which the load is 40 to be taken or discharged. Said trip-block is provided with a lateral inclined groove, i , being usually inclined upward from both its opposite ends to the middle, as plainly indicated in Figs. 2 and 3. Engagement of the dog H 45 with the tripping-block I is effected by means of a laterally-projecting lug or pin, h^2 , thereon, (seen in Fig. 4,) which pin enters the groove i . When the groove is doubly inclined said pin may enter from either end, according to the 50 direction in which the carrier approaches the trip-block. In order to hold the dog H at a proper elevation to enable the pin h^2 to enter the groove i of the trip-block I, said dog is provided with a second pin, h^3 , Fig. 4, extending laterally therefrom in position to rest on the upper edge of the adjacent carrier-plate A, and thus operating as a stop to limit the downward movement of the dog. The depending flange h' of the dog H is constructed to 55 rest on the upper end, g^2 , of the hook G when the latter is tripped, as shown in Fig. 3, and thereby holds the dog H raised. Being thus sustained, the dog, by its pin h^2 , is permanently held to the trip-block, and the carriage 60 is retained in place until the hoisting-block is raised and the hook G swung over so as to again allow the dog to descend. It is obvious

that as the lateral projection h^2 on the dog H passes out of the groove i of the trip-block the said dog is forced downward by the upper 70 wall of the groove, so that full and reliable engagement of said dog with the hook G is insured.

For the purpose of directing the yoke or eye d^2 fairly into position to be engaged by the 75 hooks of the carriage, the plates A and A' are cast in form to provide a flaring entrance, which receives and guides the yoke or eye d^2 to its proper place.

The stationary part F (shown detached in 80 Fig. 5) is provided with lateral flanges f' , which are seated between shallow ribs a^2 , cast on the inner faces of the plates A and A', and, as here shown, is additionally held in place by the tie-bolt a^3 for the plates A and A', located 85 in the entering angle of said part F. Being clamped firmly in place between the opposing plates, this part F serves, in conjunction with the bolt a^3 and bolts a^4 , joining said plates, as 90 a means of properly bracing said plates and holding them apart.

The carriage described, being provided with two pulleys, C C, and with the dog H, when combined with a tripping-block, I, having a doubly and oppositely-inclined groove, i , is obviously adapted to operate equally well at or from either side of the tripping-block, and in this respect it differs essentially from the carriages heretofore constructed, which have been provided with but a single pulley C, and have 100 required to be reversed or turned around on the supporting beam or way B in order to change their running direction. The rope E, as applied to the carriage having a single pulley d in the hoisting-block D, is made fast at 105 one end, say, by a simple knot, e , which draws against the tie-bolt a^4 , adjacent to the pulley C. To work the carriage on the way B at the opposite side of the tripping-block I from that at which it has been working, it is therefore 110 only necessary to draw the now fast end of the rope out and bring the opposite and similarly-knotted end into the same position relative to the opposite pulley C. The presence of a 115 second pulley C on the carriage, which is new in the device here presented, also allows a double sheave or pulley block, D, to be employed, as illustrated in Figs. 6 and 7. In this case the hoisting-rope is tied through one of the holes a^5 of the plate A or A', or is otherwise secured to the body of the carriage, and is thence carried under one of the pulleys d of the hoisting-block, then over one of the pulleys C, then beneath the second pulley d , and finally over the second pulley C. To provide in 125 this case for shifting the working position of the carrier from one side to the other of the trip-block I, the tied end of the rope E is released and drawn out from the hoisting-block D, and the opposite end of the rope is inserted 130 from the adjacent side and tied in the other hole a^5 . For the purpose of this change from a single to a compound tackle both a single and a double block D may be provided, or the

pulleys *d* may be changeable by means of a removable pivot-pin for said pulleys.

In the construction of the trip-block I with a doubly-inclined groove, *i*, as shown and described, it is practicable to locate several of said blocks at different points on the beam *B*, and to carry the load past as many as desired by throwing a long-handled inverted-V-shaped hook (in the hands of an attendant) over the 10 horizontal part of the rope *E* at a point close to the carriage as the latter approaches a trip-block which it is desired to pass, and pulling downward with sufficient force to bind the rope, and thus prevent the load from falling 15 while the dog is lifted and passes through the groove of the trip-block, and while, therefore, the load would otherwise be free to fall. This operation is found very convenient in many situations—as, for example, in discharging 20 sorted matters at different points along the line of the carrier.

As a result of the construction shown, the devices for engaging the hoisting-block *D* are adapted to be tripped by a block, *I*, at each 25 end of the way. Fig. 8 shows the extremities of a way, *B*, provided with blocks *I* at points where it is desired to lower the hoisting-block, either for the purpose of receiving or for discharging a load. As shown in this 30 figure of the drawings, the load is being taken from a point at the left and being delivered at a point at the right end of the sheet. In the case of a carrier system of the description shown in Fig. 8, located permanently in 35 a freight-building or similar situation, the tripping-blocks at the extremities of the way may be each provided with a groove, *i*, inclined only one way, there being no need for the outer incline, because the carriage can in no case be 40 used beyond said block; but in the case of a hay-barn system, wherein the trip-block is usually central of the way, and the hay-fork is constructed and relied on to release the hay without lowering the hoisting-block, the trip-block having the doubly-inclined groove *i* will 45 have several advantages when used in connection with a carriage in which the locking-dog is adapted to engage therewith, though said carriage have but one pulley *C*, as heretofore constructed, and needs to be reversed 50 when shifted from one end to the other of the way. In such case the block *I* should be provided with a groove on each side, and should depend centrally of the beam, so as to have 55 the same relation to the carriage whichever way the latter is turned or approached. Manifestly, working the carriage between two tripping-blocks attached to the way is an operation equivalent to working the carriage on 60 both sides of a single tripping-block, and requires in the carriage and tripping devices essentially the same features of construction; or, in other words, a carriage adapted to work between two separated tripping-blocks is 65 adapted to work on both sides of a single trip-

ping-block having a doubly-inclined groove, *i*. It is of course understood that the carriage is drawn forward upon the way by the hoisting-rope *E* after the latter has drawn the hoisting-block into engagement with the catching devices on the carriage therefor, and that said carriage is returned along the way by means of an auxiliary rope or equivalent device, which in Fig. 8 is shown as being attached to the carriage, and is lettered *e'*. In 70 the case of hay-carriers this returning-rope *e'* is ordinarily that which is connected with the hay-fork, and which also serves to unlock the said fork for the purpose of releasing the hay therefrom. 80

I claim as my invention—

1. In a carrier of the general description shown, the combination of a way, two separated trip-blocks attached to the way, and a carriage provided with devices for catching 85 and releasing the hoisting-block, constructed to work with both trip-blocks, substantially as described.

2. In combination with a way having a suitable trip-block attached thereto, a carriage provided with devices for catching and releasing the hoisting-block, adapted to coact with the trip-block when approaching the latter from either direction, and two pulleys, *C*, for the hoisting-rope, substantially as described. 90

3. In combination with the way, a trip-block having a lateral inclined groove, *i*, and a carriage, *R*, provided with devices for catching and releasing the hoisting-block *D*; whereof the locking-dog is provided with a lateral projection, *h*, for engaging said groove, substantially as described. 95

4. The tripping-block provided with a doubly-inclined lateral groove, *i*, in combination with the way, and with the carriage provided with 100 mechanism for engaging the hoist, whereof the locking-dog is constructed with a lateral projection fitted to enter said groove, substantially as described, and for the purposes set forth. 110

5. In combination with the pivoted hook *G* of the mechanism belonging to the carriage, said hook being provided with the projection *g*, the pivoted dog *H*, having a lateral pin, *h*, and constructed to rest upon the hook *G* when said dog is elevated, and the trip-block *I*, affixed to the way, and having an inclined lateral groove, *i*, for the reception of the pin *h*, substantially as described. 115

6. In combination with the carriage provided with two pulleys, *C*, a hoisting-block, *D*, provided with two pulleys, *d*, and the rope *E*, substantially as and for the purposes set forth. 120

In testimony that I claim the foregoing as my invention I affix my signature in presence 125 of two witnesses.

GUILFORD D. ROWELL.
